UNITED STATES PATENT OFFICE

2,400,381

TUBULAR ELECTRIC LAMP AND HOLDING
MEANS THEREFORWilliam R. Young, Fairfield, Conn., assignor to
General Electric Company, a corporation of New
York

Application August 22, 1944, Serial No. 550,659

8 Claims. (Cl. 176—32)

The present invention relates to tubular electric lamps such as the known fluorescent lamp and especially to such lamps wherein the envelope, instead of being straight, is in the form of a loop with its ends directly adjacent to each other. Usually, such lamps will be circular and are termed "circular" lamps but they may be oval or of other shape. Broadly, they may be termed lamps having a substantially closed configuration.

The object of my invention is to provide a tubular lamp of the type specified having an improved terminal end structure and an improved holding means for such a lamp. For a consideration of what I believe to be novel and my invention, attention is directed to the following specification and to the claims appended thereto.

In the drawings, Fig. 1 shows a circular tubular electric lamp having terminal ends and holding means therefor embodying my invention; Fig. 2 is a detail view of adjacent lamp ends and the holding means therefor on a larger scale than Fig. 1, certain parts in Fig. 2 being in section and other parts broken away; Fig. 3 is a detail sectional view taken on line 3—3, Fig. 2; Fig. 4 is a sectional view taken on line 4—4, Fig. 2; Fig. 5 is a top plan view looking in the direction of the arrow 5—5, Fig. 3; Fig. 6 is a wiring diagram; Fig. 7 is a view similar to Fig. 1 of a modification, and Fig. 8 is a sectional view taken on line 8—8, Fig. 7.

Referring to the drawings, 1 indicates a circular tubular lamp, the two ends of which are indicated at 2 and 3. Each end is sealed off as is indicated at 4 and brought out through the sealed end are the leading in wires or conductors 5 and 6 which connect with the starting coil 7. Attached over each lamp end is a metal ferrule 8, the open end of which is closed by a disk 9 of insulating material, the disk being held by crimped ends formed from material of the ferrule 8. Attached to the center of disk 9 is a terminal post 10. Surrounding terminal post 10 is a terminal sleeve 11 suitably attached to disk 9 as is indicated at 12. Between terminal post 10 and terminal sleeve 11 is insulating material 13. The leading in conductors 5 and 6 are connected to sleeve 11 and post 10, respectively. Post 10 projects beyond the end of sleeve 11. Thus, there are provided two coaxial terminals, the inner of which projects beyond the outer. The terminal posts 10 on the two ends of the lamp are in alignment with each other as are the terminal sleeves 11, the posts 10 being only slightly spaced apart as is shown clearly in Figs. 2 and 3. Ferrules 8 are so shaped that the two disks 9 are substantially parallel to each other.

The foregoing arrangement provides a lamp wherein the terminals are directly adjacent to each other and a structure which can be readily manufactured at low cost but which at the same time is amply rugged.

- 5 For use with a lamp having terminals as described, I provide a holder comprising a base of suitable insulating material having a head 14 from which projects a trough-shaped stem 15. 10 The head is open on one side, and such open side is closed by a cap 16 carried by an arm 17 provided with ears 18 by means of which it is pivoted over the open side of the stem 15 by a pivot pin 19. At 20 is a suitable spring which serves to bias cap 15 to closed position, as shown in Fig. 4. By pressing down on the end of arm 17, the arm may be turned on its pivot 19 to move the cap away from the head, as is indicated by the dotted lines.
- 20 Attached to the bottom wall of head 14 is a pair of U-shaped center contacts 21 adapted to engage with terminal posts 10 and a pair of U-shaped end contacts 22 adapted to engage with terminal sleeves 11. The U-shaped contacts 21 are fastened in position by suitable rivets 23. U-shaped contacts 22 are fastened in position by screws 24. Carried by contacts 21 and forming a part thereof are terminal screws 25. Carried by U-shaped contacts 22 and preferably formed integral therewith are terminal arms 26 which extend up into a projecting casing 27 formed integral with head 14 and adapted to receive a starter 28, the starter contact buttons engaging the ends of arms 26. Starter 28 is shown only in outline, a known form of starter being indicated. Stem 15 is provided at its end with a reduced portion 29 which is threaded to receive a nut 30 by means of which the lamp holder may be attached to a base or support 31. 32 indicates lead wires which may be attached to the binding screws 25 of the holder.
- 35 40 Fig. 6 shows a wiring diagram and from it it will be seen that the lead wires 32 are connected to the terminal posts 10 and that the terminals of the starter 28 are connected to the terminal sleeves 11.
- 45 50 The holder may be mounted on any suitable support. A lamp may be attached to the holder by pressing down on arm 17 to lift cap 16, inserting the terminals of the lamp into the respective contacts and then permitting the cap to close.

Preferably head 14 and cap 16 are provided on opposite sides with projecting ears or extensions 33 and 34 which, when a lamp is positioned in the holder, engage with the lamp ferrules 8 to

clamp the lamp and assist in holding it in the lamp holder.

With the above described arrangement where-
in the terminal posts and terminal sleeves are coaxial and concentric, it will be seen that the lamp may be turned on the U-shaped contacts as pivots so that the lamp may be brought to any desired angular position.

The holder has the advantages that it is simple in structure and capable of being manufactured at low cost. At the same time, it holds effectively the lamp and starter. By making the starter a part of the lamp holder, a compact structure results.

In connection with a lamp of this type, it is de-
sirable to have the minimum distance between the ends of the lamp so that the circle of light may be as nearly complete as possible. By my invention, I accomplish this result in a highly satis-
factory manner.

In Figs. 7 and 8, I have shown a modified form of my invention wherein the holder, instead of being provided with a pivoted cap adapted to be opened and closed, is provided with an open slot into which the lamp terminals may be moved axially. In Figs. 7 and 8, the corresponding parts of the lamp have been given the same reference characters as used in Figs. 1 to 6.

The holder comprises an insulating structure having a head 35 provided with an open slot 36 on the bottom of which are attached the two center U-shaped contacts 37 which engage the terminal posts 10 and the two outside U-shaped contacts 38 which engage the terminal sleeves 11. The head 35 is provided with a recess in which are located terminals 39 which are connected to U-shaped contacts 38 and with which engage the contacts of the starter 40. In these figures, the holder is shown as being mounted on the end of a post 41 through which the conductors 42 extend. In this construction, the lamp is attached to and removed from the holder by merely inserting the lamp terminals through the slot 36 directly into engagement with the U-shaped contacts 37 and 38.

When in position in the holder, the lamp may be turned on the U-shaped contacts as pivots to bring it to a desired angle.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:

1. In combination, an electric lamp comprising a tubular envelope shaped to bring its two ends into closely spaced parallel relationship and directed toward each other, said ends being provided with terminals comprising inner and outer coaxial contact members, the inner members projecting axially beyond the outer members, and a holder for the lamp comprising a base of insulating material and contacts carried by the base with which said terminals have pivotal engagement.

2. In combination, an electric lamp comprising a tubular envelope shaped to bring its two ends into closely spaced parallel relationship and directed toward each other, said ends being provided with terminals comprising inner and outer coaxial contact members, the inner members projecting axially beyond the outer members, and a

holder for the lamp comprising a base of insulating material having a recess, and contacts mounted in the recess with which the said terminals engage.

3. In combination, an electric lamp comprising a tubular envelope shaped to bring its two ends into closely spaced parallel relationship and directed toward each other, said ends being provided with terminals comprising inner and outer coaxial contact members, the inner members projecting axially beyond the outer members, and a holder for the lamp comprising a base of insulating material having a recess, and U-shaped contacts mounted in the recess with which the said terminals have pivotal engagement.

4. In combination, an electric lamp comprising a tubular envelope shaped to bring its two ends into closely spaced parallel relationship and directed toward each other, said ends being each provided with two terminals, one a terminal post and the other a terminal sleeve surrounding the post and insulated therefrom, the terminal post projecting axially beyond the terminal sleeve, a holder for the lamp comprising a base of insulating material having a recess, U-shaped contacts mounted in the recess with which the said terminals have pivotal engagement, and separate contacts carried by said base and being electrically connected with certain of said U-shaped contacts.

5. In combination, an electric lamp comprising a tubular envelope shaped to bring its two ends into closely spaced parallel relationship and directed toward each other, said ends being each provided with two terminals, one a terminal post and the other a terminal sleeve surrounding the post and insulated therefrom, the terminal post projecting axially beyond the terminal sleeve, and a holder for the lamp comprising a base of insulating material having a recess, and U-shaped contacts mounted in said recess with which said terminal posts and terminal sleeves engage.

6. In combination, an electric lamp comprising a tubular envelope shaped to bring its two ends into closely spaced parallel relationship and directed toward each other, said ends being each provided with two terminals, one a terminal post and the other a terminal sleeve surrounding the post and insulated therefrom, the terminal post projecting axially beyond the terminal sleeve, and a holder for the lamp comprising a base of insulating material having a recess, and U-shaped contacts mounted in said recess with which said terminal posts and terminal sleeves engage, and a cap biased toward closed position pivoted on said base for covering said recess.

7. In combination, an electric lamp comprising a tubular envelope shaped to bring its two ends into closely spaced parallel relationship and directed toward each other, said ends being each provided with two terminals, one a terminal post and the other a terminal sleeve surrounding the post and insulated therefrom, the terminal projecting axially beyond the terminal sleeve, and a holder for the lamp comprising a base of insulating material having a recess, and U-shaped contacts mounted in said recess with which said terminal posts and terminal sleeves engage, a second recess in said base, and starter contact arms connected with certain of said contacts and terminating in said second recess, said second recess being adapted to have a starter mounted therein.

8. In combination, an electric lamp comprising a tubular envelope shaped to bring its two

2,400,381

ends into closely spaced parallel relationship and directed toward each other, said ends being each provided with two terminals, one a terminal post and the other a terminal sleeve surrounding the post and insulated therefrom, the terminal post projecting beyond the terminal sleeve, and a holder for the lamp comprising a base of insulating material having a recess, and a U-shaped

contacts mounted in said recess with which said terminal posts and terminal sleeves engage, and a cap biased toward closed position pivoted on said base for covering said recess, said base and cap being provided with projecting means for clamping the lamp ends.

WILLIAM R. YOUNG.
